[57] **CLAIM**

The ornamental design for a combined boat deck and ski storage well, substantially as shown and described.

DESCRIPTION

FIG. 1 is a perspective view of the combined boat deck and ski storage well showing my new design;
FIG. 2 is a rear perspective view thereof more particularly showing the ski storage well and with the rear portion of the deck cut-away for ease of illustration;
FIG. 3 is a side elevational view thereof; and
FIG. 4 is a top plan view thereof.

FIG. 1

FIG. 2

FIG. 3

FIG. 4
